UNITED STATES PATENT OFFICE.

CLARENCE EDWARD PARKERTON, OF DANBURY, CONNECTICUT.

SPARK PLUG.

Application filed September 7, 1923. Serial No. 661,413.

To all whom it may concern:

Be it known that I, CLARENCE E. PARKERTON, a citizen of the United States, residing at Danbury, in the county of Fairfield and State of Connecticut, have invented a new and useful Spark Plug, of which the following is a specification.

This invention relates to a spark plug for internal combustion engines, which is provided with a removable terminal element for the purpose of preventing the accumulation of soot or carbon, which would reduce the efficiency of the spark plug.

The object of the invention is to provide a spark plug of this type which will be of a practical and economical construction, and in which the spark gap will also be of the correct width at the moment the spark occurs.

With the above object in view, the invention consists in the novel construction, combination and arrangement of parts which will be more particularly explained in connection with the accompanying drawing, in which,

Figure 1 is a side elevation of the spark plug constructed in accordance with my invention.

Figure 2 is a longitudinal section thereof.

Figure 3 is a longitudinal section of the body member which is adapted for connection with the spark plug hole in the engine.

Figure 4 is a longitudinal section of a spacing sleeve, which constitutes parts of the invention.

Figure 5 is an end elevation of the spark plug.

Figure 6 is an end elevation of the spacing sleeve.

Figure 7 is a section taken on the line 7—7 of Figure 2.

The spark plug, in connection with which my invention is shown, comprises a substantially cylindrical body member 10, having a reduced threaded portion 11 adapted to be screwed into the usual spark plug opening in the engine cylinder. The inner end of the body portion is adapted to project within the cylinder, and is formed into a plurality of fingers 12 separated by slots 13 to permit a portion of the fuel charge to enter the inner end of the body member 10. The inner sides of the fingers 12 form a cup-shaped recess or cage, within which

is received a metallic ball 14, which is adapted to constitute one of the electrodes.

The outer end of the body portion 10 is enlarged to form a shoulder 15, against which seats an insulating member 16 of porcelain or the like, which has a metallic core 17 projecting inwardly therefrom to form the other electrode. The outer end of the body portion 10 is also internally threaded, as at 18, to receive a bushing 19, and the insulating member 16 is formed with an enlarged portion 20, the edges of which are preferably provided with the usual metallic gaskets 21 and 22, which are clamped between the shoulder 15 and the bushing 19.

The bases of the fingers 12 are formed with shoulders 23, and a spacing sleeve 24 is received between these shoulders and the enlarged portion 20 of the insulating member 16. The inner end of this spacing sleeve is thickened, as at 25, and provided with slots 26 adapted to register with the slots 13 between the fingers 12. The fingers formed by the slots 26 have their inner surfaces concave, as shown at 27, and when the spacing sleeve is in position within the body portion 10, these surfaces 27 form a continuation of the inner surface of the ball cage, and constitute a seat against which the ball 14 is adapted to rest, thus limiting the inward movement of the ball and forming a spark gap of the proper width between it and the electrode 17.

In the operation of my invention, when the fuel charge is placed under compression, the pressure of the gases will force the ball 14 inwardly against the seat 27 to the position shown in dotted lines in Figure 2. In the usual operation of an internal combustion engine, the spark takes place at or near the moment of greatest compression, and at this time the ball 14 will form a perfect contact with the seat 27 formed on the inner end of the sleeve 24, which is grounded, and the width of the spark gap will be accurately determined. The relative length of the electrode 17 and the spacing sleeve 24 is so determined as to produce a spark of greatest efficiency, while the movement of the ball 14 back and forth under the impulses of the fuel charge during exhaust and compression will keep the spark plug entirely free from any accumulation of soot or carbon, which might interfere with its ef-

iciency. It will also be noted that the insulating member 16 may be easily removed, and in case it becomes cracked, it may be replaced at a slight expense without replacing the other parts of the spark plug.

While I have shown and described specifically one form of spark plug with which my invention may be used, it will, of course, be understood that this is merely for the purpose of illustration, and that many modifications may be made in the various parts thereof, as well as in the relation of the invention thereto, without departing from the principles of the invention as embodied in the claims.

What is claimed is:

1. In a spark plug, a substantially cylindrical metallic body externally threaded to fit the spark plug opening in the cylinder and formed at its inner end with integral spaced fingers forming a ball cage, a ball movable within the cage and forming one electrode, an insulating member removably secured within the body portion and having a metallic core constituting the other electrode, said fingers being formed with internal shoulders, and a sleeve rigidly held

between the insulating member and said shoulders with its inner end limiting the approach of the ball toward the other electrode, said sleeve being removable from the body portion when the insulating member is removed therefrom.

2. In a spark plug, a substantially cylindrical metallic body portion terminating at its inner end in spaced fingers forming a ball cage, a ball movable within the cage and forming one electrode, an insulating member removably secured in the outer end of the body portion and having a metallic core constituting the other electrode, said fingers being formed with internal shoulders, a sleeve rigidly held between the insulating member and said shoulders with its inner end thickened and slotted to form fingers, the inner faces of which are concave and adapted to form a continuation of the inner surface of the cage, providing a seat for the ball to limit its approach to the other electrode.

In testimony, that I claim the foregoing as my own, I have hereto affixed my signature.

CLARENCE EDWARD PARKERTON.
